(57) **CLAIM**

I claim the ornamental design for a container holder, as shown and described.

DESCRIPTION

FIG. 1 is a front perspective of a container holder.

FIG. 2 is a front elevation of the container holder of FIG. 1.

FIG. 3 is a rear elevation of the container holder of FIG. 1.

FIG. 4 is a left side elevation view of the container holder of FIG. 1.

FIG. 5 is a right side elevation view of the container holder of FIG. 1.

FIG. 6 is a top plan view of the container holder of FIG. 1; and,

FIG. 7 is a bottom plan view of the container holder of FIG. 1.

The evenly spaced broken lines depict portions of the design that form no part of the claim. The dot-dash broken lines in FIGS. 1-5 and 7 define the bounds of the claim and form no part of the claim.
